[57] CLAIM

The ornamental design for a digital camera for electronic computers, as shown and described.

DESCRIPTION

FIG. 1 is a top, front and right side perspective view of a digital camera for electronic computers showing my new design;

FIG. 2 is a front elevational view thereof;

FIG. 3 is a top plan view thereof;

FIG. 4 is a rear elevational view thereof;

FIG. 5 is a left side elevational view thereof;

FIG. 6 is a right side elevational view thereof;

FIG. 7 is a bottom plan view thereof;

FIG. 8 is a top, front and right side perspective view showing the article in use; and,

FIG. 9 is a top, front and right side perspective view showing the article in use in a moved position.

The broken line showing of a fragmentary computer in FIGS. 8 and 9 is for illustrative purposes only and forms no part of the claimed design.

UNITED STATES PATENT AND TRADEMARK OFFICE
CERTIFICATE OF CORRECTION

PATENT NO.: Des. 394,668
DATED: May 26, 1998
INVENTOR(S): Masaaki IINO

It is certified that an error appears in the above-identified patent and that said Letters Patent is hereby corrected as shown below:

On the title page item [22],
Delete application filing date of "Jun. 3, 1997" and insert --Jun. 30, 1997--.

Under Foreign Patent Documents add the following:

--3821/1997 2/13/97 Japan--

Signed and Sealed this

Thirteenth Day of October 1998

Attest:

BRUCE LEHMAN
